UNITED STATES PATENT OFFICE.

CHARLES STEPHEN KINNEY, OF PASO ROBLES, CALIFORNIA, ASSIGNOR OF ONE-HALF
TO PERCY A. LYLE, OF PASO ROBLES, CALIFORNIA.

STOVE.

1,297,183.

Specification of Letters Patent. Patented Mar. 11, 1919.

Application filed August 23, 1917. Serial No. 187,823.

To all whom it may concern:

Be it known that I, CHARLES S. KINNEY, a citizen of the United States, residing at Paso Robles, in the county of San Luis Obispo and State of California, have invented certain new and useful Improvements in Stoves; and I do declare the following to be a full, clear, and exact description of the invention, such as will enable 10 others skilled in the art to which it appertains to make and use the same.

My invention relates to improvements in stoves and more particularly to those known as air tight heaters, commonly used in 15 country and suburban districts for burning comparatively large chunks of wood.

The object of the invention is to provide a stove of the class described having a detachable top and an ash pan which is removable from the upper end of the stove when said top is detached, the wall of said 20 pan serving as the lining of the sheet metal casing.

With the foregoing general object in view, the invention resides in certain novel features of construction and unique combinations of parts to be hereinafter fully described and claimed, the descriptive matter being supplemented by the accompanying 25 drawings which form a part of this specification and in which:—

Figure 1 is a central vertical sectional view of the improved stove; and

Fig. 2 is a perspective view showing the 30 top and the parts carried thereby partly removed.

In the drawings above briefly described, the numeral 1 designates a vertically disposed casing which is preferably but not necessarily of cylindrical shape, said casing having a permanent bottom 2 and a 35 detachable top 3, the latter having a depending annular flange 4 which snugly surrounds the wall of the casing.

The smoke outlet 5 is carried by the casing wall, but the fuel inlet 6 is mounted on the top 3, as is also a vertical draft pipe 7, said pipe being slidable through a collar 8 so that it may be raised as the ashes accumulate. Any suitable type of draft regulator 40 9 is carried by the upper end of the pipe 7, whereas the lower end of said pipe is preferably beveled as indicated at 10.

Positioned in the casing 1, is an ash pan

11 whose wall 12 is of such height as to 55 serve as a lining for the stove, such wall having a pair of hooks or the like 13 for coöperation with other hooks 14 on a bail 15 by means of which the ash pan may be lifted from the stove after the top 3 has been removed, the latter having a pair of eyes 16 whereby the bail 15 may be employed for removing said top.

From the foregoing, taken in connection with the accompanying drawings, it will be 60 obvious that although the improved stove is of simple and inexpensive construction, it will be highly efficient and durable, particular emphasis being laid upon the fact that exceptionally large chunks of wood 65 may be placed in the stove by removing the entire top 3, and upon the detachable ash pan 12. The latter serves not only as a 70 convenient means of removing the ashes, but the wall of said pan acts as a lining for the stove which may be easily replaced when 75 burnt out. When removing the pan to dump the ashes, the top 3 with its fuel inlet 6 and the draft inlet pipe 7, are bodily removed and an external bead 7a on this pipe 80 then rests on said top as seen in Fig. 1, to prevent said pipe from possibly slipping through the collar 8.

On account of the several advantages flowing from the construction shown and described, such construction constitutes the 85 preferred form of the improved stove, but I wish it understood that within the scope of the invention as claimed, numerous minor changes may well be made without sacrificing the principal advantages.

I claim:

In an airtight stove, a sheet metal casing whose side wall is straight throughout its 95 height, a smoke outlet in said casing near its upper end, a removable sheet metal lining for said wall to shield the same against fire, the upper end of said lining being disposed immediately below said smoke outlet, a bottom secured to the lower end of said lining 100 and forming therewith a fire and ash pan removable for emptying the ashes, said bottom resting throughout its area on the casing bottom, a removable cover for said casing having a fuel inlet and an opening 105 spaced from said inlet, a one-piece vertical sheet metal draft inlet pipe slidable through said opening to permit raising of said pipe

as the ashes accumulate, and a damper on the outer end of said pipe, the lower end of the latter being beveled in one direction to permit the entrance of air, even though the lower extremity of said pipe may rest on or extend into the ashes, said cover with its fuel inlet and said draft inlet pipe being removable bodily and said pipe having an external bead to rest on said cover

and prevent said pipe from falling through 10 the opening through which it extends.

In testimony whereof I have hereunto set my hand in the presence of two subscribing witnesses.

CHARLES STEPHEN KINNEY.
